UNITED STATES PATENT OFFICE.

JOHN BROOKES AND ALBERT EDWARD TOLLEY, OF HALESOWEN, ENGLAND.

ARTIFICIAL TEETH.

Application filed August 28, 1922. Serial No. 584,702.

To all whom it may concern:

Be it known that we, JOHN BROOKES and ALBERT EDWARD TOLLEY, subjects of the King of Great Britain, residing at "Beaumont," Hagley Road, Halesowen, in the county of Worcester, England, and 27 Great Cornbow, Halesowen, aforesaid, respectively, have invented certain new Improvements in or Relating to Artificial Teeth; and we do hereby declare the following to be a full, clear, and exact description of the same.

This invention relates to artificial teeth and has for its object to provide a generally improved construction.

In artificial teeth as at present generally constructed, the complete denture usually consists of a plate to which the teeth are attached by pegging. Usually the teeth or most of the teeth are applied to the plate individually, each tooth having a peg for attaching it to the plate. In some cases, however, particularly in connection with molar teeth, two or more teeth have been formed together and attached by pegging to the plate and otherwise. This practice of attaching the teeth to the plate individually by pegging is open to the objections, first, that the teeth themselves are weakened by the holes which are formed to accommodate the pegs, and secondly, most of the teeth being constructed individually they are liable to receive greater strains than they can withstand so that breakages are comparatively frequent. Apart from breakages, the system of pegging the teeth individually to the plate is open to the objection that the teeth are liable to become loose and detached from the plate one by one. The possibility of breakage and loosening of the individual teeth is a source of considerable danger to the individual and the primary object of the present invention is to construct artificial teeth so that not only greater convenience will be obtained but much greater safety, as the present invention enables the danger of individual teeth coming loose or individual teeth breaking to be entirely overcome.

One of the features of our invention is to construct what may be termed artificial teeth "units" which comprise preferably a complete set of upper or lower teeth. These artificial teeth units, in any case, even if they do not constitute a complete set of upper or lower teeth, will usually include a

substantial number of teeth made in one piece as a single unit.

These artificial teeth units whether they constitute a complete set or not may be made with an inwardly disposed substantially horizontal flange having a number of substantially vertical perforations. Alternatively, this flange may be omitted and the perforations may be placed in the cavities at the backs of the teeth between the teeth.

Another feature of our invention is an improved method of attaching the artificial teeth units to the plate to form a complete denture and according to this part of our invention the teeth units and plate are assembled together and hot vulcanite or equivalent substance is used to unite them, the vulcanite or equivalent substance being in a substantially fluid state to enable it to pass through the holes provided in the teeth units either between the backs of the teeth or in the flange.

Referring to the drawings:—

Figure 1 is a perspective view of an upper set of teeth constructed according to this invention, the plate being shown by dotted lines.

Figure 2 is a plan view of same.

Figure 3 is a perspective view of the bottom set in its inverted position.

Figure 4 is a view of a modified form.

Figure 5 is an enlarged section.

In the construction illustrated by the accompanying drawings, the artificial teeth 1 are preferably built up so as to comprise complete sets or partial sets and are provided with an inwardly projecting flange 2. This flange 2 serves as a convenient base to which the plate 3 may be secured and is preferably provided with a series of holes 4.

The plate 3 which may be of the usual form and material is secured to the flange 2 by causing the material of the plate when in a molten condition to flow into the holes 4, the ends of the portions projecting through the holes, being preferably riveted or flanged to render them more secure. If necessary, further depressions or holes such as 5 may be formed into which the material of the plate may pass.

Instead of the inwardly extending flange 2, each unit may be provided with a number of ears or projections 6 as shown in Figure 4 through which the holes are formed.

Instead of securing the teeth units by al-

lowing the material of the plate, when hot, to flow into the holes of the units, the units may be riveted to the plate, or both methods may be used.

- 5 By employing artificial teeth constructed according to this invention, the danger of individual teeth being broken or coming off the plate is entirely avoided and a much greater degree of safety is attained.
- 10 Further, with dentures constructed in accordance with our invention the liability of small shreds or pieces of food becoming lodged or wedged between the teeth is avoided, as there are no crevices which would harbor them.
- 15 What we claim then is:—

1. An artificial denture comprising a complete row of artificial teeth formed integrally and including molars, bicuspids and 20 incisors, the upper part of said row having a plurality of small openings therein, a non-metallic plate moulded to fit the mouth, and projections on said plate entering said openings so as to unite the plate to the row of 25 teeth.
2. An artificial denture comprising a complete row of artificial teeth formed integrally and including molars, bicuspids and

incisors, an inwardly directed projecting rib upon the inner side of said row, said rib 30 being disposed below the level of the upper edge of the teeth, a plurality of small openings in the upper surface of said rib, a non-metallic plate moulded to fit the mouth, and projections on said plate entering said openings 35 so as to unite the plate to the row of set of teeth constructed according to this visible when the denture is in use.

3. An artificial denture comprising a complete row of artificial teeth formed integrally and including molars, bicuspids and incisors, the upper part of said row having a plurality of small openings therein, an inwardly directed projecting rib upon the inner side of said row, said rib being disposed below the level of the upper edge of the teeth, a plurality of small openings in the upper surface of said rib, a non-metallic plate moulded to fit the mouth, and projections on said plate entering said openings 50 so as to unite the plate to the row of teeth, whereby the said plate is virtually invisible when the denture is in use.

In witness whereof we affix our signatures.

JOHN BROOKES.

ALBERT EDWARD TOLLEY.
